SLIDING AND ROTATING BOLT LATCH

Lloyd R. Poe, Pacific Palisades, Calif., assignor to Hartwell Aviation Supply Co., Los Angeles, Calif., a corporation of California

Filed Aug. 12, 1958, Ser. No. 754,685

3 Claims. (Cl. 292—57)

This invention relates to sliding and rotating bolt latches, and included in the objects of this invention are:

First, to provide a sliding and rotating bolt latch particularly arranged to engage and draw together two abutting structures by manipulation of a handle movable between a closed position flush with a surface defined by said structures and an angular position.

Second, to provide a latch construction of this type which incorporates a novel means for effecting longitudinal sliding movement of the latch bolt for entry into a mating keeper, a rotating movement after entry into the keeper, and a sliding return movement to draw and latch the keeper and bolt together.

Third, to provide a latch construction of this type wherein alternate arcuate reciprocation of the handle effects alternate latching and unlatching of the bolt and keeper.

Fourth, to provide a latch construction which may be arranged so that the keeper member may also function as a bolt projecting between the structures joined by the latch and arranged to withstand shear loads.

With the above and other objects in view, as may appear hereinafter, reference is directed to the accompanying drawings in which:

Figure 1 is a longitudinal sectional view of the sliding and rotating bolt latch shown in its closed or locked position, and with the surrounding structures joined by the latch being shown fragmentarily and in section;

Figure 2 is a fragmentary sectional view showing a modified construction wherein the latch keeper also functions as a latch bolt;

Figure 3 is a fragmentary view of the operating shaft and its bushing taken through 3—3 of Figure 1;

Figure 4 is a longitudinal sectional view similar to Figure 1, showing the sliding and rotating bolt latch in its open position;

Figure 5 is a top view of the bolt latch with portions in section and with the structures joined by the latch shown fragmentarily and partially in plan;

Figure 6 is a transverse sectional view through 6—6 of Figure 1;

Figure 7 is a transverse sectional view through 7—7 of Figure 4;

Figure 8 is a transverse sectional view through 8—8 of Figure 4;

Figure 9 is a partial end and partial sectional view taken along the line 9—9 of Figure 4.

The sliding and rotating bolt latch may be arranged to join various types of structures. However, for the purposes of illustration, mating structures A and A' are shown which include closely spaced, parallel beams B and B' between which are mounted the elements of the latch construction. The beams are joined at their confronting ends by end members C and C' and the mating structures are covered by skin members D and D'. A slot E is formed in the skin D between the beams for

2

the accommodation of a handle for the latch construction, as will be described hereinafter.

The latch construction includes a frame 1 which may include parallel members, each in the form of an inverted U. These members are joined by end portions in which are mounted coaxial sliding bearings 2 and 3. Slidably and rotatably mounted in the bearing 2 is a bolt 4 having a head 5 formed by laterally projecting portions.

10 The bolt 4 screw threads into a coaxial operating shaft 6 and is adapted to be locked in longitudinal adjustment therein by a locking pin 7. The operating shaft 6 is slidably and rotatably mounted in the slide bearing 3 and projects therebetween to terminate in a ratchet head 8, which in the drawing is shown as having four ratchet teeth disposed at 90° intervals. The bearing 3 is provided with a pair of diametrically disposed quadrant slots 3a, and the shaft 6 is provided with a cross pin 6a which rides therein. The pin and slots cooperate with the ratchet head 8, as will be brought out hereinafter.

Slidable on the operating shaft 6 between an abutment ring 9 and the head 8 is a slide spool 10 having external flanges at its axial ends. A spring 11 interposes between the ring 9 and the spool 10 and urges the spool towards the head 8.

25 The slide spool 10 is provided with a helical slot 12, preferably occupying a 90° arc, and is arranged to receive a roller 13 extending laterally from the operating shaft 6, so that on relative axial movement of the spool and operating shaft a corresponding relative helical movement occurs.

30 Mounted on the slide spool 10 is a sleeve 14 which is capable of limited sliding movement between the end flanges of the spool. The end of the sleeve 14 remote from the ratchet head 8 is provided with a tooth 15 adapted to engage into any one of four positioning notches 16 provided in the flange at the corresponding end of the spool 10.

35 The end of the sleeve 14 nearest the head 8 is provided with an internal flange 17 overlying the corresponding end of the spool 10 which is arranged to engage the head 8. The sleeve 14 carries an axially extending ratchet-engaging lever 18 which overlies the head 8 and engages its ratchet teeth. A spring 19 bears against the lever 18 to urge the lever radially inward into engagement with the teeth of the ratchet head 8.

40 The sleeve 14 is provided with diametrically disposed bearing recesses which receive journal elements 20 in the form of internal bosses at the extremity of an operating yoke 21. The operating yoke constitutes a lever or link member which extends upwardly and forwardly or toward the frame 1 and is journaled on a transverse shaft 22 mounted in a handle member 23.

45 The handle member 23 is preferably formed of sheet material and is channel-shape in cross section so that the shaft 22 is journaled between the flanges of the channel-shape handle member. The handle member 23 is provided near the shaft 22 with a second transverse or fulcrum shaft 24, the extremities of which ride in slots 25 provided in the frame 1. The frame itself is secured by mounting bolts 26 between the beams B of the structure A. Reinforcing links 24a extend between the shafts 22 and 24.

50 The handle member 23 fits within and fills the slot E and occupies a flush position therein when the latch is in its closed position. The handle member 23 is provided with a slot in which is journaled an auxiliary latch lever 27, which may also be formed of sheet material and is of channel-shape cross section so that the latch lever 27 may be disposed flush with the web of the handle member 23.

The latch lever 27 is pivotally supported relative to the handle member 23 by a journal pin 28. The latch lever 27 extends downwardly from the handle member 23, that is, toward the axis of the operating shaft 6, and terminates in hook elements 29 adapted to engage a cross pin 30 when the handle member is in its closed position, such as shown in Figure 1.

The slide bearing 2 may be arranged to fit within the aperture formed in the end member C so that the head 5 of the bolt 4 may project beyond the structure A and into the mating structure A'.

Mounted between the beams B' of the mating structure is a keeper 31 which is U-shaped in plan. A cross portion or web 32 of the U-shaped keeper may register with an opening provided in the end member C' and aligns with the bearing 2 and bolt 4. The web 32 is provided with a bore 33 which receives the bolt 4 and is provided with side slots 34 to accommodate the laterally projecting portions of the head 5 when the bolt is properly oriented relative to the keeper 31.

Operation of the sliding and rotating bolt latch is as follows:

The handle member 23 is connected through the yoke 21 to the sleeve 14 in such a manner that pivotal movement of the handle member 23 between the closed position shown in Figure 1 and the angular position shown in Figure 4 causes the sleeve 14 to reciprocate on the operating shaft 6. Outward movement of the handle member causes the sleeve 14 to move in the direction of the bolt 4. This outward movement causes the tooth 15 to engage in one of the positioning notches 16 so as to restrain the sleeve from rotation.

Initially the sleeve 14 and operating shaft 6 move in unison, the operating shaft being moved by reason of the spring 11 interposed between the sleeve and the operating shaft. During this initial movement, the bolt head 5 moves clear of the keeper 31. During this initial movement, the cross pin 6a is within the bearing 3 and engages one arcuate extremity of each slot 3a to prevent rotation of the shaft 6 in one direction, whereas a notch on the ratchet head 8 prevents rotation in the opposite direction.

Continued movement of the handle member 23 causes the sleeve 14 to move forward relative to the operating shaft 6 so that the helical slot 12 acts on the roller 13 to cause a quarter turn of the operating shaft, bolt, and head as soon as the pin 6a clears the bearing 3, as shown in Figure 4. This movement brings the head into alignment with the side slots 37 in the keeper 31 so that the bolt head may be withdrawn.

Return movement of the handle member 23, that is, movement in a clockwise direction from the position shown in Figure 4, causes the entire assembly including the sleeve 14, operating shaft 6, bolt 4, and head 5 to move rearwardly. During this movement, the ratchet-engaging lever 18 engages the ratchet head 8 and the cross pin 6a engages the shoulders formed by the quadrant slots 3a, to prevent rotation of the operating shaft 6, bolt 4, and head 5, but the sleeve 14 is permitted to make a quarter turn. Thus, on return of the handle member 23 to the position shown in Figure 1, or to approximately this position, the bolt 4 is retracted and the bolt head remains in the position to which it was turned during the opening movement of the handle; that is, the bolt head occupies a position 90° from the position shown in Figure 1, in alignment with the slots 37 in the keeper 31.

When the handle member 23 is again moved counterclockwise from the position shown in Figure 1, the shaft 6 and bolt 4 first move forward and are held against rotation until the pin 6a clears the bearing 3 and the head 5 has passed through the keeper 31, whereupon the interaction of the helical slot 12 and roller 13 turns the head 5 into locking position. Clockwise movement of the handle member 23 from the position shown in Fig-

ure 4 to the position shown in Figure 1 first causes the head 5 to rotate and then causes the bolt 4 to be retracted, drawing the two structures A and A' together.

In the construction shown in Figure 1, the bolt 4 constitutes the shear member between the two structures A and A' and also the tension member therebetween. However, as shown in Figure 2, the keeper 31 may be converted into a bolt member 31a and the bolt 4 converted into a tension or draw member 4a with a draw head 5a. In this construction, a slide bearing 2a is substituted for the slide bearing 2 and is provided with a keeper recess 2b. The bolt member 31a is provided at its cross portion or web with a bolt extension 31b adapted to enter the recess 2b. Except for the fact that the members 4 and 5 cease to be a bolt and head, but instead a draw bar 4a and draw head 5a, the interaction of the draw head 5a and bolt member 31a are the same as in the first described structures. The draw bar 4a serves merely as a tension member, shear stresses being taken by the bolt extension 31b.

While particular embodiments of this invention have been shown and described, it is not intended to limit the same to the exact details of the constructions set forth, and it embraces such changes, modifications, and equivalents of the parts and their formation and arrangement as come within the purview of the appended claims.

What is claimed is:

1. A latch construction, comprising: a guide frame; a bolt slidably and rotatably mounted therein and having a keeper-engaging head adapted for engagement with a mating keeper when in a first angular position and to clear said keeper when in a second angular position; an inner rotatable sleeve and an outer nonrotatable sleeve on said bolt; helical groove and pin means to effect a predetermined relative angular movement of said inner sleeve and bolt on reciprocation of said bolt; means carried by said outer sleeve to restrain said inner sleeve against rotation during movement relative to said bolt in one axial direction; means carried by said outer sleeve and bolt to restrain said bolt against rotation during movement of said bolt in the opposite axial direction; said means cooperating with said head to move said head alternately between said first and second positions; and handle means for reciprocating said bolt.
2. A latch construction adapted to be mounted in a pair of confronting structures; a handle mounted in one of said structures and movable between a position flush with said structure and an angular position extending therefrom; a guide frame; a bolt slidably and rotatably mounted therein, and having a keeper-engaging head adapted for engagement with a mating keeper when in a first angular position and to clear said keeper when in a second angular position; an inner and an outer sleeve on said bolt; helical groove and pin means to effect a predetermined relative angular movement of said inner sleeve and bolt on reciprocation of said bolt; means restraining said outer sleeve against rotation; means carried by said outer sleeve to restrain said inner sleeve against rotation during movement relative to said bolt in one axial direction; means carried by said outer sleeve and bolt to restrain said bolt against rotation during movement of said bolt in the opposite axial direction; said means cooperating with said head to move said head alternately between said first and second positions; and an operating link interconnecting said handle and bolt.
3. A latch construction, comprising: a guide frame; a bolt structure axially slidable and rotatable in said guide frame, and including a keeper-engaging head at one end arranged for movement between a keeper-engaging position and a keeper-releasing position, and a transversely disposed operating pin; an inner sleeve axially and rotatably movable on said bolt structure and defining a helical slot to receive said pin to effect relative rotation of said inner sleeve and bolt structure upon relative reciprocation thereof; a spring urging said inner sleeve to

one axially and rotationally extreme position relative to said bolt structure; an outer sleeve journaling said inner sleeve and having limited axial movement relative to said inner sleeve; connecting means joined to said outer sleeve to retain said outer sleeve against rotation; a handle for operating said connecting means to effect axial movement of said outer sleeve thereby to effect axial movement of said inner sleeve and bolt structure; ratchet and pawl means carried by said outer sleeve and bolt structure to limit rotation of said bolt structure relative to said outer sleeve to one direction, said means tending to stop said bolt structure in its keeper-engaging or its keeper-releasing positions; cooperating notch and tooth means carried by said inner and outer sleeves for interlocking

said inner and outer sleeves when in one axial relation, and to free said inner sleeve when in their opposite axial position, said ratchet and pawl means and notch and tooth means being alternately operable, whereby on reciprocation of said sleeves and bolt structure said bolt structure is caused to rotate progressively between alternate keeper-engaging and keeper-releasing positions.
